UNITED STATES PATENT OFFICE

CHARLEY ANN CROWLEY, OF NASHVILLE, TENNESSEE

HOLDER FOR REKNITTING FABRICS

Application filed March 22, 1932. Serial No. 600,546.

This invention relates to holders for knitted fabrics, and more particularly it relates to holders over which stocking and other knitted fabrics are positioned while runs, 5 ravel and the like therein are being repaired.

Heretofore a glass or egg cup has been used and over which the fabric is stretched taut by grasping it in the hand and pulling it downward. The present invention consists in the provision of a holder or last which is illuminated from the inside and diffuses a light through a transparency closing the pocket or recess provided in the last for 15 accommodating the illuminating element.

Further, the invention consists in the provision of an illuminated last having all the advantages of sunlight, and little or no disadvantage of an electric or artificial light, 20 the latter being especially undesirable as being injurious to the eyes.

The invention together with its numerous objects and advantages will be best understood from a study of the following description, 25 taken in connection with the accompanying drawing wherein:

Figure 1 is a side elevational view of the last or holder.

Figure 2 is a top plan view thereof, and 30 Figure 3 is a vertical sectional view taken on the line 3—3 of Figure 2.

Referring more in detail to the drawing it will be seen that 5 designates generally a last or supporting device and which may be 35 of any desired shape and constructed of suitable material. It has been found desirable, in actual practice, to make the last 5 of wood, metal, glass or clay and preferably of the 40 shape shown, that is substantially cylindrical and tapering toward one end, and intermediate the ends being provided with a circular groove forming a neck 6.

The last 5 is provided with an axial 45 pocket or socket 7 that is substantially of uniform diameter throughout its length, and which opens at the smallest end of the last as shown. Adjacent its open end the socket 7 is provided with an annular shoulder 8 which supports a transparent disk 9. 50 The disk is preferably made of glass and is

removably secured in place between the shoulder 8 and a split expandable ring 11 formed of metal or other suitable material. A ring 11 fits in the circular groove 12 provided above the shoulder 8 so as to accommodate the ring 11 in such a manner that a portion of the ring will engage the glass 9 as 55 shown in Figure 3.

Suitably anchored within the socket 7 at the closed end thereof is a light socket 13 with which is suitably engaged an electric bulb or lamp 14. An electric light cord is designated by the reference character 15 and one end of the cord passes through an obliquely disposed opening 16 provided in the 60 peripheral wall of the last 5 adjacent the bottom of the socket 7 and is suitably connected with the socket 13. On its free end the cord 15 is provided with a suitable plug 17 for engagement with an outlet socket or 65 other electrical device affording connection with a suitable source of electrical supply.

In actual practice, either the disc 9 or the bulb 14 is colored whereby to eliminate undesirable rays emanating from the bulb 14 70 that the light diffused thereby will as nearly as possible be similar to sunlight. Such light rays are desirable, since being similar to natural or sunlight, will be least injurious to 75 the eyes.

In use, the last is used in substantially the same manner as a glass or egg cup is now used, the hose or other fabric to be mended being stretched taut over the last with the portion thereof to be mended being disposed over the smallest end of the last 5 and in this way, the operation of darning will be greatly facilitated.

Even though I have herein shown and described the preferred embodiment of the invention, it is to be understood that I do not wish to limit myself to the precise details of construction, combination and arrangement of elements as herein shown, but claim all 80 such forms of the invention to which I am entitled in view of the requirements of the prior art and the scope of the appended claim.

Having thus described my invention, what I claim as new is:

A darning last for supporting a fabric 100

having a run therein to be reknitted comprising a substantially elongated cylindrical body provided with a socket opening at one end of said body, said socket adjacent the 5 open end thereof being counterbored to provide an annular shoulder inwardly from the open end thereof, a transparent disk engaging said shoulder, a split ring in the counterbore of said socket and bearing against the outer 10 face of said disk at the marginal edge of the latter, and a lamp within said socket at the inner end of the latter.

In testimony whereof I affix my signature.

CHARLEY ANN CROWLEY.
